MACHINE FOR PACKAGING MERCHANDISE
ROLLS

Carl J. Gerlach, Green Bay, Wis.

Application November 3, 1947, Serial No. 783,822

7 Claims. (CL 93—2)

1

This invention is directed to a novel machine or device for automatically and continuously wrapping paper rolls and to the method of tucking and forming the ends of paper roll packages and to continuous application of the wrappers or labels to the roll packages as the same are continuously fed through the device.

It is an important object of my invention to provide an automatic machine of the described class which includes a driven means for regulating the feeding of paper rolls to the machine; a means for applying a strip of glue to the feed rolls; an elevator for supporting a stack of labels or wrappers in the path of the rolls being fed and whereby each roll will pick up one label to cause it to be rolled or enveloped about the paper roll; means for applying a second area of glue to each paper roll as it is passing above the label stack; means for continuing the rolling movement of the paper roll until the adhesion of the second area of glue completes affixation of the opposite end portion of the label to the paper roll; a driven slotted-rotatably mounted annular conveyor member into the slots of which the rolls are fed successively, and mechanical driven means for twisting, folding and forming the opposite end portions of the wrappers substantially flat against the opposite ends of the paper rolls.

A further object of my invention is the provision of means for automatically pressing and folding against the ends of paper rolls the opposite end parts of a wrapper or label surrounding the paper roll, and for delivering the fully wrapped rolls to manually accessible positions to be packed into containers and the like.

A further object of my invention is the provision of automatic means for applying intermittently glue areas to a traveling paper roll, first applying one glue area and causing it to pick up and roll a label about it and applying a second glue area just before completion of the enveloping movement, and thereby mounting the label or wrapper about the roll in a cylindrical form.

A further object of my invention is the provision of a mechanical elevator for a stack of labels or wrappers and power driven means for slowly raising said elevator so as to cause the uppermost of a stack of labels to be maintained at a level so that a glue-bearing paper roll during its enforced travel will pick up such uppermost label.

A further object of my invention is the provision of mechanical means, in cooperation with a rotatable conveyor for paper rolls which have

2

projecting wrapper end portions, which is adapted to intermittently press and twist inwardly and successively the oppositely projecting portions of the labels or wrappers of the paper rolls so as to form a compact package.

Other and further important objects of my invention will be apparent from the following description and appended claims.

This invention (in one preferred form) is illustrated and described in the following specification having numerals of the references borne on the accompanying drawings.

On the drawings:

Fig. 1 is a side elevational view of my machine with the side wall removed so as to show interior parts, and with certain parts broken away.

Fig. 2 is a top plan view of the machine with upper wall removed.

Fig. 3 is an enlarged view looking at a section of the jack shaft.

Fig. 4 is an enlarged side elevational view of the glue applying means and the driven belts for forcing the rolls along their path of travel and over the stack of labels.

Fig. 5 is an enlarged view looking at a section of the rotatable conveyor taken on line V—V of Fig. 1.

Figure 6 is a cut away plan view showing the mounting means for one of the tuckers.

Figure 7 is a side view of a part of machine showing the driving means for rotating one of the end forming members.

Figure 8 is a plan view of a part of the machine showing the container and glue applying mechanism.

Figure 9 is a plan view of Figure 8.

Figure 10 is a view in elevation of the glue container and glue wheel.

Figure 11 is a front view of Figure 10 showing the glue wheel and part of the drive means therefor.

Figure 12 is a top view of a part of the machine showing part of the drive mechanism for the elevator.

Figure 13 is a perspective view of part of the machine showing the pawl drive mechanism for the elevator.

Referring to the drawings, reference numeral 10 designates a frame which includes a base 11, end walls 12 and 13 and two side walls 14 and 15, only the side wall 14 being shown in Fig. 1. Said walls are assembled and secured together by suitable fastening elements (only parts of which are shown in Fig. 1).

Numeral 16 represents a suitable support or

table, only part of which is shown at the left of Fig. 1, and from which rolls of paper are delivered to the machine over the upper edge of wall 12.

Referring to the left part of Fig. 1, numeral 17 is a vertical panel which, together with the side wall 15, carries a shaft or pin 18 on which is pivotally mounted a motor shelf or base 19. An electric motor 19a is secured by bolts to said base 19 so that said motor will keep drive belt 26 at the proper tightness.

Mounted and journaled in suitable bearings secured on the inside faces of side walls 14 and 15 is a jack shaft 22 on which is mounted a pulley 23. A pair of smaller grooved pulleys 24 and 25 are securely mounted on shaft 22. A belt 26 transmits power from the motor pulley to the pulley 23 and shaft 22. Another grooved pulley 27 is secured on said shaft 22 (as shown in Fig. 3) and which is adapted to drive an endless feeder belt as hereinafter described.

As shown in Fig. 1, a curved metal longitudinally slotted apron 28 extends from the upper edge of wall 12 to one end wall of a label container or magazine hereinafter described. A metal guard 29 is suitably secured above apron 28 to provide an entrance chute or tunnel for paper rolls.

Description of means for holding labels and for raising same to desired level during continuous operation

As shown in Fig. 1, numeral 30 designates a tubular vertical member which is secured on base 31 which is secured to base 11. Slidably mounted in member 30 is a post or tubular element 32 which has suitably secured thereon a vertical rack bar 33 whose teeth are partially exposed through an opening in the upper part of member 30 (as also shown in dotted lines in Fig. 2).

As shown in Fig. 2, a stub shaft 34 is horizontally journaled in wall 15 and in a suitable bracket 35 (which is secured on the side of member 30). Said shaft 34 has a pinion 36 secured thereon, said pinion meshing with rack bar 33. The other end of shaft 34 has a toothed sprocket or ratchet gear 37 thereon (see Fig. 2). As shown in Fig. 2, the outer projecting end of the shaft has a hand wheel 102 thereon to selectively operate said shaft manually.

As shown in Fig. 1, secured on the upper end of slidable element 32 is a flat elevator support or panel 39 which is movable within a stationary upwardly opening bottomless magazine guide member or container 38 comprising four vertical connected wall panels for labels or wrappers, and which container is supported by suitable brackets with respect to the frame, as shown in Fig. 2. The dimensions of the elevator member 39 and container 38 may be varied to accord with the size of labels or wrappers used.

Numeral 40 designates a speed reducer secured angularly on a base 41, which base is secured to the bottom base member 11.

Speed reducer 40 has a lower driven shaft 42 which carries pulley 43 and an endless belt 44 transmits power from the jack shaft 22 through pulley 25 and through pulley 43 to the speed reducer. As shown in Fig. 1, an upper driving shaft 45 has pulley 46 secured thereon and a dog or pawl 47 has one end pivoted non-concentrically on an eccentric stud member which is mounted on shaft 45.

Shaft 105 is journaled in a pair of spaced apart bearings 106 and in a plane above shaft 45, as shown in Figs. 1 and 2. The opposite pointed

end of pawl 47 is normally held in engagement with sprocket or ratchet wheel 37 by a spring 48 which is anchored to side wall 15. A short dog 49 is mounted on one end portion of a rockable journaled handle 108 which is journaled in side wall 15. The outer bent end of said handle 108 permits selective manual gravity descent of the elevator. Dog 49 engages the teeth of ratchet wheel 37 to prevent its clockwise rotation. Shaft 10 45 and pulley 46 are driven clockwise. An endless belt 121 drivingly connects pulleys 46 and 104 (see Fig. 2).

As the ratchet wheel 37 is slowly driven counter-clockwise, the pinion 36 is correspondingly rotated, and this causes the rack bar and elevator to rise at the desired speed so as to substantially maintain the uppermost of the stack of labels in alignment with the inner end portion of the apron 28 and so that the fed rolls 20 will have a substantially straight path.

Description of roll feeding means and glue applying means

25 Metal upwardly extending brackets or arms 112 and 113, which carry anti-friction bearings 125 in their upper ends, are secured at their lower ends to the spaced apart transverse bar 123, which bar extends horizontally and is suitably secured at its ends in side walls 14 and 15, as shown in Fig. 2. Shaft 50 is journaled in bearings 125.

30 Upwardly extending metal brackets 114 and 115 (shown in end view in Fig. 2) have their lower ends suitably secured on the second horizontal bar 124 whose ends are suitably secured to the side walls 14 and 15. Said brackets 114 and 115 have suitable bearings 126 mounted in their upper ends on which is journaled shaft 51.

35 As shown in Fig. 3 vertically extending frames 110 and 111 are supported in spaced apart parallel relation by shafts 50 and 51, said shafts being journaled in suitably spaced passages in said frames. Said frames provide a means for supporting the glue containing and applying devices herein described.

40 Shaft 50 has secured on one end thereof a pulley 54 (Fig. 9) which is driven from jack shaft 22 and pulley 27 through an endless belt 55. A pair of flat pulleys 56 are secured in spaced position on shaft 50 (see Fig. 3), and a pair of flat pulleys 57 are secured in spaced position on shaft 51 as shown in Fig. 9. A pair of endless flat belts 58 are mounted on and ride on aligned pulleys 56 and on aligned pulleys 57 respectively.

45 Shaft 50 has a small pulley 59 secured thereon which is connected by an inverted round belt 60 to drive a larger pulley 61 which is secured on shaft 62 (as shown in Fig. 1). Shaft 62 is journaled in suitable passages in side walls 14 and 15, as shown in Fig. 2.

50 As shown in Fig. 1, a star wheel or roll separator 64 is secured on shaft 62 so that its arms 65 will rotate clockwise through a central slot of apron 28 and regulate the feeding of the delivered rolls so that same are fed one at a time and at the proper speed to the trackway below belts 58.

55 Referring to Figs. 8 and 9, a glue container 65 is secured by means of screws and a bracket 66 on frames 110 and 111. A glue roller 67 is mounted on journaled glue shaft 117. Said shaft is journaled in bracket 116. This shaft has extensions on either side to which are fastened

flat pulleys 118 and 119 which ride on belts 58 and are turned by same.

Glue container 65 has a slotted opening 120 in one end thereof as shown in Fig. 10, in which a part of glue roller 67 is disposed. As shown in Figs. 8, 9, 10 and 11, a manually adjustable vertically movable scraper and closure element 63 is slidably mounted in an apertured ear 63a, which ear is carried by one end of container 65 and in a vertical passage in bracket. Said scraper 10 63 also acts as an adjustable closure for the slotted outlet opening as recess 120 in container 65. Scraper and closure 63 is provided with a grippable handle 63b. A pair of screws 63c (as shown in Figs. 8, 10 and 11) are provided to adjust vertically and secure bracket 103 in desired position according to the amount of liquid glue to be allowed to pass to roller 67.

Glue roller 67 is so disposed that the wound paper rolls falling through the chute will contact said glue roll and thereby cause adhesion of a strip or area of glue on each roll. The rolls will continue to roll as indicated in Fig. 1 so that such first applied glue area will contact the forward edge portion of the uppermost label of the stack of labels. The frictional engagement of the moving belts 58 will continue to roll each paper roll and wind a label partly about it. When each roll reaches a predetermined point, a second glue roller 68 will be contacted by the paper roll to thereby apply another strip of glue to the surface of the paper roll adjacent to the first part of the label already cemented to the roll.

As shown in Fig. 9, roller 68 is journaled on a 35 suitable shaft 69, which shaft in turn is journaled in aligned passages of a bracket 70. Bracket 70 is secured by screws to a horizontal cross bar 53 as shown in Fig. 9.

Numerical 71 designates a second slotted glue 40 container which is secured on bracket 70 as shown in Fig. 9. An adjustable closure and scraper 52 is slidably mounted on the end of said glue container to provide for selectively adjusting the glue outlet and to regulate the amount of glue which will be carried by glue roller 68.

As the paper roll is continued in its rolling movement by the belts 58 the end portion (to which glue has been last applied) will be pressed against the wound paper roll to complete the mounting of the label or wrapper into cylindrical form and with its end portions projecting beyond the opposite ends of the paper roll.

Description of mechanism for tucking, folding and forming the end portions of the labels or wrappers

A shaft 71 has its opposite ends journaled in bearings 72 and 72a (see Figs. 1, 2 and 4).

As shown in Fig. 2, a driven pulley 73 on the 60 end of shaft 71 is driven clockwise (looking at Fig. 1) through endless belt 78 from pulley 24 on jack shaft 22.

A short sleeve 75 is rotatably mounted on shaft 71 and has securely mounted on it two spaced 65 apart pulleys 73 and 77 as shown in Fig. 2. Pulley 76 on the outer end of shaft 71 is driven through an endless belt 74 from pulley 104 on shaft 105, which shaft and pulley in turn are driven from the speed reducer through belt 121, 70 which belt drives pulley 104a.

This causes a rotation of shaft 71 at a speed slower than the rotating speed of sleeves 75 and 75a. Pulley 77 transmits rotation to the rotatable tucking and sliding shafts hereinafter de- 75

scribed through two round belts 91 which ride on two series of pulleys 90 and 83 (see Fig. 7).

As shown in Fig. 2, the opposite end portion of shaft 71 is journaled within a metal sleeve 15a which in turn is journaled in wall 14 by means of bearing 72. A pulley 13a is secured on the outer projecting end of sleeve 15a and said pulley is driven by a twisted belt from pulley 24a on jack shaft 22 in a direction counter to the direction of rotation of sleeve 75.

79 designates a metal wheel-like roll conveyor having a plurality of relatively deep and wide recesses 80 opening on its periphery as shown in Fig. 1. Said recesses or pockets are of sufficient size to receive a normal size paper roll. A plurality of flat ended projections 79a are thereby formed between said recesses respectively.

Secured on both sides of said conveyor are a plurality (preferably 10) of angularly offset metal radially extending metal tucking and journaling brackets 109, each of which is secured by four screws 81 to the side face of the conveyor as shown in Figs. 5 and 6. Said journaling brackets are bifurcated at their outer ends and such bifurcated portions have aligned apertures therein in which are slidably and rotatably mounted metal relatively short tucking shafts 82, as shown in Figs. 1 and 2. Secured on each of the shafts between the adjacent bifurcated ends of the bracket is a small grooved pulley 83. Each shaft preferably has a ball bearing 96 mounted in its outer end portion.

As shown in Fig. 2, the inner end of each of the tucking shafts 82 carries an enlarged member 84, on the inner end of which is secured the reduced end portion of a spiral spring 85 whose free end is relatively larger.

Each of the bifurcated end portions of brackets 109 has a second pair of holes transversely through it and in which is slidably mounted a headed guide rod 86 which is parallel to and spaced from the adjacent shaft 82. The inner end of each guide rod 86 is bent substantially at right angles and is connected to member 84 of each such shaft 82, respectively. Mounted upon each guide rod 86 is a metal expansion spring 87 whose expansive action normally presses the adjacent shaft 82 to outward projected position and away from the wheel-like conveyor 79.

Horizontally extending on each side face of conveyor 79 and in equal spaced apart perpendicular positions partly beneath the brackets 109 are an equal number (preferably 9) of fixed shafts 88 which extend transversely, though parallel, with respect to shafts 82 in brackets 80.

Each of said shafts 88 has an idle pulley 90 secured at its free end, which pulleys are in alignment with corresponding pulleys 83 on shafts 82. Said pulleys 83 are in alignment with those pulleys 90 which are on the same side of the conveyor.

As illustrated in Fig. 7 an endless belt 91 is mounted about pulley 77 on sleeve 75 and in zig-zag relation about each outer pulley 83, and alternately about the adjacent idler pulleys 90, as illustrated in Fig. 1 in dotted lines.

As the belt 78 is driven from pulley 104 the sleeve 75 is rotated clockwise and the belt 91 is rotated clockwise and in turn the respective pulleys 83 and shafts 82 will be rotated clockwise. There are two of the belts 91 (only one being shown in Fig. 1), and two groups of the pulleys 77; the second pulley 77a being on the opposite side of the conveyor (see Fig. 4). There are also 10 mounting brackets carrying 10 shafts

82 and corresponding adjacent parts on the side of the conveyor opposite to the viewer of Fig. 1.

Secured by bolts on the inside of the opposite side walls of the frame walls 14 and 15 and adjacent the outlet end of the machine are two cam blocks or tracks 93 and 94, as shown in Fig. 2. When the outer ends of shafts 82 pass the faces 94a and 93a of said cam blocks, the rotating shafts 82 will slide back and be returned to original positions by the expansive action of springs 87 respectively on guide rods 86 to the degree permitted by their mountings and during such return, the same will slide along the inclined faces 94b and 93b of said cam blocks.

Referring to the right hand part of Fig. 1, numeral 112 designates a side view of a curved metal apron which has a large central recess (not shown) through which the end portions of conveyor 79 pass during rotation. Said apron is secured on end wall 13 by suitable screws (not shown), said wall having a delivery opening through which the rolls roll out as illustrated.

Numerical 113 designates an end section of an endless conveyor belt mounted upon a roller or pulley 114 which is journaled on a suitably mounted shaft 116. Said conveyor section is merely illustrative and not a part of my machine.

The wound rolls of paper roll into the space and channel between guard 29 and apron 28. Star wheel 64 is rotated clockwise, its shaft 62 being driven from a pulley on shaft 50 through a twisted belt. The arms of star wheel 64 pick up only one paper roll at a time and feed same into the space below belts 58. As the roll has passed through the channel before it has been engaged by the star wheel it has engaged the glue roll 68 so that a spot of glue adheres to its outer face.

The belts 58 are rotated counter-clockwise (looking at Fig. 1) through belt driven connecting pulleys 27 and 54 on shaft 22. Belts 58 cause each paper roll to roll to the right, and the spot of glue first applied to the roll adheres to the end edge of the top-most label of the stack of labels causing such label to be wound about the roll.

When the paper roll has reached a point slightly past mid-way the engagement thereof with roller 68 applies a second spot or area of glue to the face of the roll which is so faced that when the roll of paper reaches the spaces below the right-hand end portion of the two belts 58 the right-hand end portion of the top-most label will be pressed into contact with the spot or area of glue also applied to the face of the roll by the roller 68. Accordingly the special adhesion will hold the paper label or wrapper in cylindrical form with opposite end portion thereof projecting outwardly.

As each roll with wrapper mounted thereon in the manner described passes out from under the belts 58 and along the metal apron 98 it will engage the end face of one of the projections 79a of the roll conveyor, and as the conveyor 79 is rotating in a clockwise direction looking at Fig. 1, the roll will fall into the first recess 80 by gravity, and each succeeding roll will likewise successively fall into such recesses 80 respectively.

As the conveyor rotates in clockwise direction the ball bearings 96 on the end of the slidable shafts 82 will engage the gradually inclined trackways or faces 93a and 94a respectively of the two mounted and opposite blocks 93 and 94 respectively. As the rotating movements continue the shafts 82 are gradually pressed inwardly as

indicated in Fig. 2, and at the same time the shafts 82 shown in the lower part of Fig. 2 are rotated clockwise, and the shafts 82 on the opposite side of the machine are rotated clockwise with respect to a viewer looking at the machine from the top side of Fig. 2. Accordingly the spiral springs 85 are rotated clockwise simultaneously with the movement toward conveyor 79, with the result that the enlarged end portions of said spring 85 frictionally engage oppositely cylindrical portions of the wrappers or labels so as to twist such projecting label portions spirally and press such portions against the opposite ends of the paper roll. As such rotating and inwardly pressing action is simultaneous against opposite projecting parts of the label or wrapper and is of substantially equal force the paper rolls will continue to be maintained within said recesses 80.

As the outer end portions of the shafts 82 and their bearings 96 pass the innermost portions of the track faces 93a and 94a, the shafts will gradually return to their outer original positions as their end portions slide along the beveled faces 94b and 93b respectively of blocks 94 and 93. When each roll has moved to the right-hand part of the machine, the bifurcated curved portions of the apron 112 will engage the opposite end portions of each roll to cause each such roll with wrapper thereon to be rolled outwardly from the conveyor recesses and out through the exit opening in the end wall 13 of the machine to fall by gravity either into a receptacle (not shown) or upon an endless conveyor 113 as mounted on pulley 113a, only fragment of which is illustrated in Fig. 1.

As the successive rolling of rolls of paper in the manner described causes successive picking up of the labels or wrappers as described, the elevator 38 is relatively slowly raised upwardly by the described mechanism which includes the reciprocating pawl 47 driven through shaft 45, successively engage the teeth of sprocket 31, which in turn slowly rotates shaft 36 and pinion 36 causing relatively slow elevation of rack bar 33 and consequent elevation of the tubular element 32, elevator support 39 and the wrappers and labels thereon. The ratio of movement is adjusted through the relative ratio and sizes of the mentioned pulleys, the speed reducer and said sprocket and driven pinion so that the uppermost of a stack of labels or wrappers will be maintained in substantially a plane tangential with respect to circumferences of the rolls fed by the belts 58.

The present invention has been described here-
55 in more or less as to details, yet it is to be understood that the invention is not to be limited thereby, as changes may be made in the arrangement and proportion of parts and equivalents may be substituted without departing from the spirit and scope of the invention.

I claim:

1. In a machine for wrapping cylindrical roll packages, and including a driven mechanism for rolling and feeding the roll packages, an adjustable vertically movable elevator, a walled container disposed above said elevator said container being adapted to hold a stack of labels with the uppermost in the path of the packages, a driven mechanism for gradually raising said elevator, a driven means for applying two separate glue areas to the packages, said labels being adapted to stick to said packages when said packages are rolled on said labels, and means to fold, twist and form the projecting portions of the labels over the ends 70 of the contents of the packages; said last men-

tioned means comprising a driven wheel-like annular conveyor having spaced peripheral recesses adapted to receive the packages with labels rolled thereon having end portions projecting beyond the contents; a plurality of apertured spaced journalling brackets secured on each side of said annular conveyor; a plurality of slidable shafts journaled with respect to said rotatable conveyor and having end portions extending outward and having the opposite ends thereof extending inward with respect to said conveyor; spiral springs mounted on the inner ends of said slidable shafts; spring elements connected to said shafts for returning same to outward non-operating positions driven mechanism for rotating said shafts on said conveyor; and a pair of stationary cam tracks mounted adjacent each side of conveyor; said shafts, upon rotation of said conveyor, being adapted to engage said cam tracks respectively to cause inward sliding of said shafts during their rotation and during the rotation of said conveyor; said spiral springs on the inner ends of said shafts being adapted to be thereby rotated to thereby twist and fold the projecting parts of labels or wrappers against the ends of the roll units.

2. In combination, a conveyor having a plurality of peripheral recesses adapted to receive rounded merchandise packs upon each of which a paper wrapper has been rolled with the end portions of the wrapper projecting substantially beyond the ends of the merchandise packs; power driven mechanism for moving said conveyor; a plurality of offset journalling brackets mounted on opposite sides of said conveyor; a short shaft slidably mounted and journaled in each of said brackets; means for rotating said shafts; said shafts being aligned with the central part of said recesses respectively; spiral springs on the inner ends of said shafts; mechanism for rotation of said conveyor; a cam block mounted on each side of said conveyor and in a path to be engaged by the outer ends of said shafts respectively; the rotation of said shafts and springs during movement of said conveyor causing said springs to twist and fold the opposite projecting portions of the wrappers of the merchandise packs; and means for returning said shafts to their outer positions.

3. In a machine for wrapping cylindrical packages including a driven mechanism for regulating the feeding of such packages successively, a wrapper applying means, and a glue applying mechanism; a driven turret-like conveyor having a plurality of peripheral package receiving recesses therein; a plurality of journalling brackets in spaced relation secured on opposite sides of said conveyor; a rotatable shaft carried by and slidably in each of said brackets and substantially perpendicularly to said conveyor; inwardly extending yieldable springs on the inner ends of said shafts respectively; driven mechanism for rotating said shafts and springs; elongated stationary cam blocks mounted adjacent opposite sides of said conveyor; said shafts, when said conveyor is rotated, successively engaging said cam blocks to thereby cause inward movement of said springs; the movement of said conveyor being adapted to carry the label-bearing packages in an arcuate path during which movement said rotated springs will engage the projecting label end portions to crimp and fold same against the ends of said packages respectively.

4. A label applying machine substantially as recited in claim 3 and including mechanism for rotating the shafts and springs thereon on one

side of said annular conveyor in one direction and the shafts and springs on the opposite side of said conveyor in the opposite direction during simultaneous rotation of said annular conveyor

5 whereby the projecting opposite end portions of each label on each package will be twisted and folded in opposite directions.

5. In a device for holding and crimping the end portions of wrappers of substantial cylindrical merchandise packages, said machine having a driven annular peripherally recessed conveyor; a plurality of journalling brackets connected on opposite sides of said conveyor; a shaft slidable and rotatable in each of said brackets; inwardly projecting yieldable springs on the inner ends of said shafts; elongated stationary cam tracks mounted at opposite sides of said conveyor; a guide rod journaled in each of said brackets and having one of its ends connected to the adjacent 10 slidable shaft; a return spring mounted on each of said guide rods; said shafts being adapted to slidably engage said cam tracks to cause inward movement of said shafts and said springs, the rotation of said shaft and springs during movement of said conveyor causing said springs to rotate and thereby fold and crimp the opposite projecting end portions of wrappers of merchandise packages carried in the recesses of said conveyor, the engagement of said shafts with said tracks, when said conveyor is rotated, being adapted to cause inward movement of said shafts and springs operatively connected to said shafts; said return springs being adapted to return said shafts to their outer positions.

6. In a machine for wrapping wrappers about a cylindrical merchandise object, means for applying a wrapper about said object so that each wrapper has loose oppositely projecting parts substantially defining a cylinder; a driven annular conveyor having a plurality of spaced apart recesses opening on the periphery of said conveyor; a plurality of apertured journalling brackets secured on both sides of said conveyor; slidable and rotatable shafts journaled in said brackets, said shafts being disposed in substantial alignment with the central portion of said recesses; driven mechanism for said shafts and for moving said conveyor said shafts being rotatable independently of said conveyor; a pair of stationary cam tracks mounted substantially adjacent the opposite sides of said conveyor; yieldable spiral springs on the inner ends of said slidable shafts; the outer ends of said shafts being adapted to successively slide on said cam tracks to cause gradual inward sliding thereof and the rotation of said shafts and of said springs thereon being adapted to cause twisting and folding movements of the projecting end portions of the wrapper and to pack such wrapper end portions against the opposite ends of the merchandise rolls; and spring means operatively connected to said slidable shafts to return same to outermost positions after same have disengaged said cam tracks.

7. In combination with a machine for applying and folding wrappers or the like about merchandise packages, said machine having a supporting frame and a turret-like conveyor rotatably mounted with respect to said frame and being movable in a vertical plane, said conveyor having a plurality of spaced, peripheral package-receiving recesses, and having means for feeding packages successively to said recesses; a plurality of spaced apart journalling brackets secured on opposite side faces of said conveyor and in positions substantially adjacent said conveyor recesses, the

brackets on opposite sides of said conveyor adjacent each recess being in substantial alignment with each other; a shaft slidably and rotatably journalled in each of said brackets and being substantially perpendicular to said conveyor; driven mechanism for selectively rotating on one side of said conveyor in one direction and for rotating the shafts on the opposite side of said conveyor in an opposite direction; a plurality of inwardly projecting yieldable wrapper-engaging springs secured to the inner ends of said shafts respectively; guide rods journalled in said brackets respectively and secured to the ends of said shafts respectively; spring means on said rods for returning same to outer positions; and stationary elongated cam tracks connected to said frame and being on opposite sides of said conveyor in the normal path of travel of the outer ends of said shafts, the rotation of said conveyor carrying said shafts into engagement with said cam tracks to thereby cause progressive inward movement of said shafts and said yieldable springs, the simultaneous rotation and inward movements of said shafts causing said yieldable springs to fold and form the opposite end portions of the wrappers 25

against packages, said spring means retracting said shafts upon disengagement thereof from said cam track.

CARL J. GERLACH.
